DESCRIPTION

U.S. PATENT DOCUMENTS

FIG. 1 is a front elevational view of a multifunctional cold insulation container showing my new design, the rear elevational, left side elevational, and right side elevational views being identical thereto;

FIG. 2 is a top plan view thereof;

FIG. 3 is a bottom plan view thereof;

FIG. 4 is a top perspective view thereof; and,

FIG. 5 is a bottom perspective view thereof.
